TROLLEY WIRE CONTACTOR

Samuel S. Matthes, Mansfield, Ohio, assignor to
 The Ohio Brass Company, Mansfield, Ohio, a
 corporation of New Jersey

Continuation of application Serial No. 208,421,
 May 17, 1938. This application August 9, 1939,
 Serial No. 289,166

4 Claims. (Cl. 246—254)

My invention relates to trolley wire contactors for use in the operation of signals, lights, electrically operated switches, etc. through the medium of a passing current collector.

5 This application is a continuation in whole of my application Serial Number 208,421, filed May 17, 1938.

One of the objects of my invention is to provide a device in which the various parts which are 10 subject to wear may be easily and conveniently renewed.

Another object is to provide a device which may be adapted to various wire conditions by merely changing certain parts, thus avoiding the necessity of making up an entire new device for each 15 wire condition.

Other objects will be hereinafter disclosed and be evident to those skilled in the art.

My invention resides in the new and novel 20 construction, combination and relation of the various parts disclosed in this specification and the accompanying drawing and set forth in the claims.

In the drawing:

25 Fig. 1 is a view in elevation of my invention.
 Fig. 2 is a top view of Fig. 1.

Fig. 3 is a bottom view of Fig. 1.

Fig. 4 is a view in partial section taken on the line 4—4 of Fig. 2 in combination with a current 30 collector.

Fig. 5 is a side view of one part of my invention which I term the body member.

Fig. 6 is a side view of one part of my invention which I term the arcing tip.

35 Fig. 7 is a top view of Fig. 6.

In the preferred embodiment of my invention I make use of a body member 1 of predetermined length. The body member comprises an elongated web 2 having a threaded boss 3 by means of 40 which the device is attached to an overhead support. The web portion 2 is provided at its ends with transverse openings 4 and 5 and is, also, provided with intermediate transverse openings 6.

The web portion 2 is, also, provided with an 45 upper flange 7 and lower flanges 8 and 9 which add materially to the strength of the body member in resisting bending.

To each end of the body member is secured a detachable end 10 which is provided with spaced flanges 11 forming therebetween a groove to receive the end portion 12 of the web 2. The flanges 11 are provided with transverse openings which register with the openings 4 in the portion 12 of the web and the member 2 and the end 55 members 10 are secured in position by means of through bolts 13.

The end members 10 and the body member 1 are of metal and in electrical contact.

50 The end members 10 are provided with means for receiving the ends of the trolley wire 14. As

there are many types and sizes of trolley wire, it is advantageous in many ways to have the end members 10 detachable from the body member 1, thus making it possible through the use of a single body member to adapt the device to the various sizes and styles of trolley wire by merely forming the end members 10 to meet the different wire conditions then applying them to the body member as required.

5 The trolley wire 14 is held in position by means 10 of set screws 15.

Intermediate the ends of the body member 1 is a contact member 16 provided adjacent each end with a pair of spaced lugs 17. Each pair of lugs is provided with transverse openings which 15 register axially with the openings 6 in the body member 1.

In the class of devices in which this invention falls it is important that the contact member 16 be insulated from the trolley wires 14 and, therefore, I place an insulating bushing 18 in each opening 6 and insulating washers 19 on opposite sides of the web 2 and interposed between the web and lugs 17.

20 The contact member 16 is held in position with 25 respect to the body member 1 by means of through bolts 20. If desired, the insulation between the contact member and the body member may be modified from that disclosed, but I find the arrangement described simple and efficient. 30

The ends of the contact member 16 are spaced 35 a somewhat considerable distance from the ends of the members 10 and 1 position in such space arcing tips 21, each provided with a pair of spaced lugs 22 provided with openings 23 which register 45 with the openings 5 in the body member 1.

Each arcing tip 21 is in contact with the body member 1 and has one face 24 abutting the adjacent end face 25 of the end member 10 or in very close relation thereto. The other face 26 40 of the arcing tip 21 is spaced from the adjacent end face 27 of the contact member 16 and the faces 26 and 27 are parallel but disposed diagonally with respect to the longitudinal axis of the device.

50 The lower surfaces 28 of the trolley wire and 55 29 of the arcing tip 21 and 30 of the contact member 16 are in alignment, thus permitting a smooth passage of the current collector 31 across the device and when the collector 31 passes from the part 21 to the part 16 or vice versa, it will contact with each of these parts simultaneously thus eliminating entirely or to a large extent any arcing in making such passage.

The part 21, however, is easily detached and 55 replaced with a new part as is also the part 16. The parts 10 and 21 being of the same polarity and electrically connected through the member 1, no arcing takes place as the current collector 60

passes even though the parts may be slightly separated.

As the member 21 is held in position by a single fastening device 20, I brace the free end 5 of the member 21 with respect to the body member 1 against upward pressure of the current collector by means of a lug 32 which may be cast integral with the member 21 or may be a separately formed lug inserted in a cavity 33 and 10 may be of metal or insulating material.

By constructing the end of the body portion 1, as shown and described, it is possible whenever 15 desirable to attach the body member to other devices used in overhead trolley construction by forming a cooperating part on said device.

The member 16 is provided with a connecting part 34 to receive a conductor from the device to be operated, as for instance the operating coil of an electric switch. Since the member 16 is 20 insulated from the trolley wire 14, current may be drawn through the said operating coil when the current collector 31 engages the member 16.

Having described my invention others skilled in the art will recognize modifications which may 25 be made and which may fall within the scope of my invention and, therefore, I wish to be limited only by my claims.

I claim:

1. A trolley contactor for the purpose described comprising in combination, an elongated body member of metal, means for attaching the body to a support, detachable end means at each end of the body, transversely disposed means to secure the detachable means to the body in electrical contact therewith, each detachable end means provided with means to receive a trolley wire end and means to removably secure the trolley wire in position, an elongated contact member detachably secured to the body member 30 intermediate its ends and having its lower surface adapted to contact with a current collector and in alinement with the lower surface of the trolley wire, a pair of spaced lugs at each end of the contact member to receive therebetween the body member, registering transverse openings in the lugs and body member, insulating members positioned in the openings through the body member and between the body member and the lugs to insulate the contact member from the body member, transversely disposed means at each end of the contact member extending through the said openings to detachably secure the contact member to the body member, a pair of renewable arcing tips electrically secured to the body member, one tip at each end of the contact member between the end of the contact member and the detachable end means, each tip having one end face abutting the detachable end means and the other face spaced from the adjacent end face of the contact member and the said end faces parallel and obliquely disposed to the longitudinal axis of the contactor whereby a moving current collector will engage simultaneously both the contact member and the arcing tip in passing from the one part onto the other, the lower surface of the arcing tip being in alinement with the lower surface of the contact member and the trolley wire.
2. In a trolley wire contact device comprising 70 in combination, a pair of spaced end members of metal each adapted to receive and hold a trolley wire end and a separately formed elongated body

member of metal having ends to which the end members are secured to hold the end members in fixed and electrically connected relation and also having a pair of spaced arcing tips of metal, each tip secured to the body member adjacent an end member and electrically connected thereto, the combination with the body member of a contact member of metal having two pairs of upstanding lugs, one pair adjacent each end of the contact member and forming a groove within which the body member is secured in insulated relation to the contact member, the adjacent ends of the contact member and arcing tips being lapped but spaced and transverse means extending through the lugs and body member to secure the body and contact together and means insulating the body from the contact member.

3. In a contact device for the purpose described, having an elongated body of metal, metallic end members, one at each end of the body secured thereto by tongue and groove joints and transverse means to prevent displacement and hold the parts in electrical connection, each end member having a straight groove along one edge to receive an end of the trolley wire without bending and with its lower edge exposed and also having means to hold the wire in place, arcing means electrically and detachably secured to the body to extend in effect the inner ends of the end member towards each other, the combination with the body of an elongated contact member of metal positioned between the inner ends of the arcing means and having a pair of spaced upstanding lugs adjacent each end between which the body is positioned and from which the body is insulated, the contact being of such length as to be spaced from each end of the said arcing means, means extending through the lugs and body to detachably secure the contact member in place and insulating means positioned between the lugs and the body to insulate the body and contact member, the adjacent ends of the contact member and of the arcing means being lapped but spaced such that a passing current collector will be in engagement with both parts at the same time and means associated with the contact member to secure a conductor thereto.

4. In a trolley wire contact device comprising in combination, a pair of spaced end members of metal each having means to receive and hold a trolley wire end and a separately formed elongated body member of metal having ends to which the end members are secured to hold the end members in fixed relation to the body member and to each other and also having a pair of spaced arcing tips of metal, each tip secured to the body member adjacent an end member and electrically connected to the adjacent end member, the combination with the body member of a contact member of metal having spaced upstanding means adjacent the ends of the contact member to secure the contact member to the body member, the adjacent ends of the contact member and the arcing tips being lapped but spaced and means to secure the spaced upstanding means to the body member to secure the contact member to the body member and means associated with the body member whereby the contact member and the end members are insulated from each other.
